FREQUENCY MULTIPLIER AND AMPLIFIER

Application filed March 23, 1927. Serial No. 177,505.

This invention relates to frequency multipliers, and more particularly to a method and means for obtaining frequency multiplication and amplification in the successive power stages of a short wave transmitter.

5 Crystal control is desirable in order to maintain constant frequency, but it is found that crystals ground to have a frequency greater than that corresponding to about a 100 meter wave are too delicate for practical handling and utilization. Modern practice dictates the use of waves as short as 15 meters, and even less, and accordingly it is an object of my invention to make possible 10 the use of a low frequency crystal for the control of a high frequency transmitter. This I do by employing frequency multiplication in the successive power stages of the amplifier of the transmitter.

15 The use of frequency multiplication with crystal control is not new, but heretofore it has been customary to use such frequency multiplication only for external controlling energy obtained from a master oscillator. The high frequency low power output from 20 the master oscillator was used to control the frequency of power amplifier systems, all the stages of which were tuned to the high frequency. This method was used because it 25 was the most obvious one and because vacuum tubes have not been considered efficient 30 from an energy standpoint when used as frequency multipliers. The frequency multiplication has therefore been restricted to the small frequency control energy alone.

35 However when short waves with correspondingly high frequencies are used great difficulty is encountered due to feed back of energy from the output circuit to the input 40 circuit of each stage of the amplifier, which tends to make the stage oscillate independently of the frequency control energy, and also due to energy feed back from the higher power to the lower power stages of the amplifier, which tends to cause the whole chain or system of amplifiers to oscillate independently of the frequency control energy.

45 The principal object of my invention is to eliminate this difficulty due to feed back of energy and to prevent the tendency for oscil-

lation independent of the control energy. This I do by multiplying the frequency of the control energy in each stage of the amplifier. When this is done the effect of feed back from the output to the input circuit of 55 each stage of the amplifier is very greatly reduced because the circuits are tuned for and operate at greatly different frequencies. The input circuit does not respond to currents from the output circuit because it is not 60 tuned for the frequency of these currents and therefore it does not cause radio frequency potential to be brought back to the control electrode in a manner to cause oscillation such as would obtain in the ordinary amplifier where the input circuit is tuned to the 65 frequency of the current in the output circuit. Also the effect of feed back from the higher power to the lower power stages is very great- 70 ly reduced because of the very great difference in the operating frequency for which each stage is tuned. A still further gain is made in freedom from feed back difficulties because all stages but the last operate at lower frequencies than the final output from the sys- 75 tem and this lower operating frequency in itself lessens the amount and effect of the feed back of energy.

80 A further object of my invention is to improve the energy efficiency of a vacuum tube when used as a frequency multiplier and amplifier at the same time. This I do by adjusting the power stage in which the tube is used so that anode currents flow for only a brief fraction of the time duration of a half 85 cycle. In the next place, I have found that at high frequencies, because the magnitude of the tube capacitance becomes great relative to the input circuit capacitance, there is an appreciable degenerative effect. Although 90 this effect is very much less than in a stage used as an amplifier without frequency multiplication, still it is very beneficial at the higher frequencies to compensate for this degeneration. This compensation may even 95 be carried beyond the point where the degeneration becomes zero and some regeneration may be used without causing oscillation, as would be the case in the ordinary amplifier, and this improves the energy efficiency of the 100

vacuum tube. This compensation of the degeneration, or else positive regeneration, by the addition of regeneration of the same amount or else more than the degeneration is 5 accomplished by bringing energy back from the output circuit at the harmonic output frequency and with it applying a potential to the grid of the tube which is opposite in phase to the harmonic high frequency potential on the anode.

By making the amplifier stages efficient although used as frequency multipliers my invention obviates the necessity for using separate frequency multipliers and their associated equipment and thereby saves both in original outlay and in power consumption.

It is sometimes desirable to arrange a frequency multiplier and amplifier stage to obtain an even harmonic, with consonant suppression of the odd harmonics, or an odd harmonic with suppression of the even harmonics. In still other cases it may prove desirable to have a single arrangement which is capable of delivering either an odd or an even harmonic. Accordingly, it is a further object of my invention to provide circuits for even harmonic, odd harmonic, and all harmonic amplifiers.

The more complete specification which follows is accompanied by drawings in which:

Figure 1 shows potential and current curves for efficient frequency doubling;

Figure 2 is a wiring diagram for an amplifier stage;

Figure 3 shows potential curves for the circuit in Figure 2;

Figure 4 is a wiring diagram for an all harmonic amplifier;

Figure 5 is the circuit of Figure 4 rearranged in the form of a bridge;

Figure 6 is a wiring diagram for an even harmonic amplifier;

Figure 7 is the circuit of Figure 6 rearranged in the form of a bridge;

Figure 8 is a wiring diagram for an odd harmonic amplifier; and

Figure 9 is the circuit of Figure 8 rearranged in the form of a bridge.

In Figures 5, 7 and 9 certain immaterial elements have been omitted.

It is possible to get very nearly full rated power from a tube even though used for an output frequency which is a multiple of the input frequency. Referring to Figure 1 it will be seen that the curve of grid voltage e_g , which is substantially the same as that for any vacuum tube amplifier when adjusted to operate at high efficiency, swings above the line of holding or grid biasing potential only at the peak of the positive half cycle of input potential. In consequence the plate current i_p flows during only a brief fraction of the duration of a positive half cycle of input potential. With this condition there may be obtained in the plate circuit a plate voltage

e_p , either of frequency F , or of a harmonic frequency, exemplified in this case by the double frequency $2F$. For high efficiency, vacuum tubes are operated in the manner shown even when no frequency multiplication is sought. Inasmuch as the power output is measured by the product $i_p e_p$, and the current i_p flows only during the short interval of time during which e_p is passing through its most negative values, and at that time e_p is the same for both the fundamental frequency and the harmonic frequency, it follows that the product $i_p e_p$ is almost as great for operation on the harmonic as for operation on the fundamental. This efficient production of harmonics without reduction in energy output from the tube can, of course, be anticipated only when limiting the operation to the lower harmonics.

Referring to Figure 2, input energy is fed by means of the coil L_1 to a coil L_g , which, together with the condenser C_g , forms an input circuit tuned to the input frequency. The output circuit $C_p L_p$ is tuned to the harmonic frequency, and is connected to the cathode by condenser C_1 and a direct current source. There is a natural tube capacitance, represented by C_T . The grid is maintained at the biasing or holding potential by, for example, any suitable source of negative biasing potential of suitable value. As shown in Figure 1, the biasing or polarizing potential of the grid of the tube 2 of Figure 2 is maintained at a proper negative bias such that plate current flows during only a brief fraction of the duration of a half cycle of positive input alternating potential. Accordingly, with the single tube arrangement of Figure 2, when the output circuit is tuned to a harmonic of the input, it oscillates freely for a period of time greater than the time of a harmonic cycle before another impulse of excitation energy is received from the plate.

For the higher harmonic frequencies the input circuit becomes an effective capacitance, because the inductive reactance is increased and the capacitive reactance is decreased. We may therefore consider that there is a circuit from the anode to the filament consisting of the two condensers C_T and the effective capacity of the input circuit in series. At very high frequencies the capacitance C_g becomes small, and the capacitance C_T becomes quite large relative to C_g , consequently we can no longer assume that most of the potential drop from anode to filament takes place across the capacitance C_T . As the reactance of C_T decreases the potential drop across it decreases and consequently a larger portion of the total potential fluctuation takes place across C_g , and it is this potential fluctuation measured across the grid condenser which is effective at the grid. In general the grid and anode potentials fluctuate 180 degrees out of phase,

but this feed back energy is practically in phase, and therefore is degeneration.

These relations are shown by the curves in Figure 3. Curve A represents the grid potential of fundamental frequency; curve B shows the resulting anode potential if the anode circuit is tuned for the fundamental; curve C represents the anode potential if the anode circuit is tuned to the double frequency, and it is to be noted that this curve, like curve B, is in phase opposition to the grid potential during the positive or effective half-cycles of the latter; and curve D shows the grid potential caused by feed back through the condenser C_1 , and this is in phase with the anode potential, as shown by curve C, thus causing degeneration.

Attention is now directed to Figure 4, which is similar to Figure 2 except that the steady anode potential is applied at point y , the midpoint of the inductance L_p , and there has been added a condenser C_N . If the condenser C_N is adjusted to equal C_T in capacitance the output circuits are thereby made symmetrical with respect to the grid, and the circuit is neutralized.

As in the arrangement shown in Figure 2, and as described in Figure 1, the grid of the frequency multiplier tube of Figure 4 is maintained at a negative potential such that plate current flows only during a brief fraction of the positive half cycle of input potential.

Figure 4 has been redrawn in Figure 5 in the form of a bridge. It is clear that since points x and y are each at mid-potential with respect to the alternating anode potential across the bridge at points a and b there can be no potential difference between points x and y , for the harmonic frequency, and consequently none across the condenser C_N , as a result of which there will no longer be degeneration.

In order to obtain regeneration in an exceedingly simple manner, according to my invention C_N is made to have greater capacitance than C_T , that is, the circuit is over-neutralized. From the diagram in Figure 5 it can be seen, if condenser C_N is made greater than C_T in capacitance, and therefore less in reactance, that point x , instead of being at mid-potential or ground potential with reference to the anode harmonic frequency, will have a potential value dependent upon the difference in the capacitance, that is, upon how far away from the mid-point of the cathode-anode potential gradient the grid is shifted, electrically, and that this potential will be 180 degrees out of phase with respect to the anode potential. The circuit then is regenerative.

The arrangement so far described is an all harmonic amplifier, equally well adapted for the production and amplification of even or odd harmonics.

If it is desired to arrange the stages so that each will utilize two tubes arranged with their control electrodes in phase opposition it becomes necessary to use a special circuit according as even or odd harmonics are to be developed. It is quite easily arranged, if the fundamental frequency is multiplied to an even harmonic, that the odd harmonics be completely suppressed, and vice versa. The use of two tubes is often desirable not only to get an increased energy output but also because if they are oppositely excited they deliver energy to the output circuit at more frequent intervals than when a single tube is used and so a pure undamped continuous wave current is more closely approached in the output circuit.

The relation between the anode current and potential in a vacuum tube may be expressed by the equation $i = AE^x$ in which A and x depend upon the characteristics of the tube. Letting

i_{p1} = the anode current in the first tube,
 i_{p2} = the anode current in the second tube,
 E_p = the steady anode potential,
 u = the amplification factor of the tubes,
 E_c = the steady grid potential,
 e = the maximum alternating grid potential, and
 wt = the input frequency, we may write:

$$i_{p1} = A (E_p + u E_c + ue \sin wt)^x$$

$$i_{p2} = A (E_p + u E_c - ue \sin wt)^x$$

In the above equations the term involving wt is the input energy applied to the tube grids, and since these are in phase opposition, there is a difference in algebraic sign, as indicated. If these expressions are expanded into series and rearranged to show the harmonics it is found that the even harmonics have like algebraic signs, and the fundamental and odd harmonics have unlike algebraic signs. To indicate the idea in a very simple way assume that the exponent x has a value of 2.

Substituting 2 for x , expanding to remove the exponent, and then substituting for $\sin^2 wt$ its value in terms of double the angle,

$$\frac{1 - \cos 2wt}{2},$$

we obtain

$$i_{p1} = A(E_p + uE_c)^2 + \frac{Au^2e^2}{2} - \frac{Au^2e^2}{2} \cos 2wt + 120$$

$$2A(E_p + uE_c)(ue \sin wt)$$

$$i_{p2} = A(E_p + uE_c)^2 + \frac{Au^2e^2}{2} - \frac{Au^2e^2}{2} \cos 2wt - 125$$

$$2A(E_p + uE_c)(ue \sin wt)$$

In the above equations the terms involving $2wt$ are the second harmonic, or double frequency, while those involving wt are the fundamental frequency. It is important to notice that if the outputs of the two tubes are

added algebraically then the second harmonic outputs of each will be combined in phase, while the fundamental will be combined out of phase, and eliminated. On the other hand, if the outputs of the two tubes are combined subtractively, then the even harmonic is eliminated, and the fundamental is added in phase.

In actual practice the exponent is not 2, but is variable over a wide range in the course of a single cycle, and various other harmonics result. However, the relation of the algebraic signs will be as indicated in the simple case chosen, and in general, if the outputs of the two tubes are added in parallel then the even harmonics are obtained, and the odd harmonics are cancelled, and on the other hand, if the output of the two tubes is combined in series, or push-pull, then the even harmonics are cancelled and the odd harmonics are obtained.

In Figure 6 there is shown an even harmonic amplifier. Input energy is supplied to the coil L_1 , which is coupled to the coil L_g . The latter, together with the capacitance represented by the series combination C_{g1} and C_{g2} , forms an input circuit which is tuned to the input frequency, and which is connected, as shown, to the grids of the tubes T_1 and T_2 in series, or phase opposition. The anodes of the tubes T_1 and T_2 are directly connected in parallel to one side, b , of the output circuit $C_p L_p$, which is tuned to an even harmonic of the input frequency. This connection gives algebraic addition of the tube outputs, and the desirability of this was before pointed out. The other side of the output circuit, a , is connected through a neutralizing and regenerative feed back condenser C_N to the mid-point of the potential gradient across the input tuning condensers. The circuit from anode to cathode is made from point y , which is at the mid-point of the alternating potential gradient across the output circuit, through a blocking condenser C_1 and a source of direct anode potential, not shown. The natural tube capacitances are indicated by C_{T1} and C_{T2} .

As described in connection with the curves of Figure 1, the grids of the tubes of the circuit shown in Figure 6 are maintained at a negative potential such that only the peaks of positive input potential cause plate current to flow.

The circuit has been redrawn in the form of a bridge in Figure 7, and it is easily seen from this figure that C_N may be given a value which will make the points x_1 and x_2 be at mid-potential, or ground potential, and therefore have the same potential as mid-point y in the output circuit, in which case there will be no degenerative potential applied to the grids G_1 , G_2 . As before explained, in accordance with my invention the capacitance C_N may not be adjusted for exact neutralization, but instead may be so adjusted that the points x_1 ,

x_2 are moved above the mid-point on the potential gradient between a and b , thereby placing upon the grids G_1 and G_2 a potential of frequency equal to the output frequency, and in phase opposition with respect to the potential on the anodes P_1 and P_2 , thereby increasing the amplification.

If odd harmonics are desired and even harmonics are to be suppressed, it is merely necessary to arrange the output circuit as well as the input circuit in series or phase opposition with respect to the tube electrodes. Such a circuit has been shown in Figure 8, in which $L_g C_g$ is an input circuit, tuned to the input frequency, and connected to the tubes T_1 , T_2 in phase opposition, while $C_p L_p$ is an output circuit, tuned to an odd harmonic of the input frequency, and connected to the tube anodes in series or phase opposition, that is, it is so connected to the tubes that their outputs are combined subtractively, in contra-distinction to the arrangement in Figure 6 in which the outputs of the two tubes are combined additively.

Natural tube capacitance is represented by C_{T1} and C_{T2} , and to provide regeneration the feed-back condensers C_{N1} and C_{N2} are connected as shown. This arrangement is quite similar to a neutralizing arrangement already known in the art but this prior neutralizing arrangement has not been applied to a frequency multiplier. Also it is important to note that the so-called neutralizing condensers may be made greater than the tube capacitance in order to obtain regeneration in a most simple manner and without such a great tendency for oscillation as is met with in the ordinary amplifier used in the prior art.

In the arrangement shown in Figure 8, the grids, as described in connection with Figure 1, are maintained at a negative potential such that plate current flows only during a brief portion of the peak of positive input potential applied to each tube.

Figure 9 shows the circuit of Figure 8 redrawn in the form of a bridge. When C_{N1} is made equal to C_{T1} , and C_{N2} is equal to C_{T2} , the grids G_1 and G_2 are at mid-potential or ground potential with respect to the output frequency, although, of course, their potentials vary oppositely at the input frequency. When the condenser C_{N1} is made larger than natural capacitance C_{T1} , point x_1 moves downwardly on the potential gradient between a and b , whereby potential of the output frequency but of opposite phase to that upon the anode P_1 is impressed on the grid G_1 , resulting in regeneration. Similarly, when the condenser C_{N2} is made greater than the natural capacitance C_{T2} , point x_2 moves upward with respect to mid-potential, and therefore varies at output frequency in opposite phase with respect to the anode P_2 . In effect, the grids G_1 and G_2 vary in phase op-

position with one another, at output frequency, and this is in effect a push-pull input at the output frequency, serving to accentuate the harmonic.

- 5 In all of the arrangements disclosed it may be mentioned that because the input circuit is not tuned to the output frequency the adjustments for regeneration are not at all critical, and the desired amount of regeneration may be easily approached without danger of swinging over into self-oscillation. This is in marked contrast to the extremely critical adjustment required to prevent oscillation of the ordinary amplifier 10 when used at very high frequencies. I have found that at frequencies corresponding to 15 meters variations in capacitance of tubes and circuits due to mechanical movement resulting from temperature variation is alone sufficient to seriously handicap continuous 15 operation of the ordinary amplifier.

In actual practice it is found that the amplifier stages may be operated almost as efficiently and almost at the same power rating on a low harmonic as on the fundamental with the further advantage that the transmitter is greatly simplified, not only by the entire omission of special frequency multipliers for a master oscillator, but also by 20 reason of the fact that only the output circuit of the last stage need be accommodated to the high transmission frequency, and each of the preceding circuits operates at progressively lower and more easily handled frequencies, with which only a smaller percentage of energy need be wasted in circuit 25 losses.

The foregoing modifications have been disclosed by way of illustration and not limitation of my invention, which I claim is:

1. In apparatus of the character described, an electron discharge device having within an hermetically sealed container an electron emitting cathode, an electron receiving anode, and a control electrode intermediate said cathode and anode for controlling the flow of electrons from said electron emitting cathode to said anode, a circuit comprising an inductance coil and a condenser 45 connected in parallel connected across said control electrode and cathode, said circuit being tuned to a fundamental frequency, a circuit comprising an inductance coil and a condenser connected in parallel connected 50 between said anode and cathode, the circuit constants of said last mentioned circuit being such as to resonate at a frequency corresponding to a harmonic of the frequency of said circuit connected across said control electrode and cathode, means for subjecting 55 said control electrode to a negative potential with respect to said cathode, and means for energizing said circuit connected across said control electrode and cathode with energy of 60 fundamental frequency corresponding to the tuning of said circuit connected across said

control electrode and cathode, the control electrode of said electron discharge device being subjected by said negative biasing means to a negative potential of a value such that for only brief fractions of positive input alternating potentials applied to said control electrode, plate current flows through said device from said cathode to said anode, whereby said circuit connected between said anode and cathode is caused to have engendered therein electrical oscillations of harmonic frequency, which oscillations oscillate freely for periods of time greater than the time of a cycle at the harmonic frequency intermediate successive times when plate current flows through said tube from said cathode to said anode.

2. In combination, an electron discharge device; a tunable input circuit tuned to a fundamental frequency directly connected to the input terminals of the electron discharge device; a tunable output circuit, tuned to a harmonic of the fundamental frequency, directly connected to the output terminals of the electron discharge device; and means for subjecting the control electrode of the device to a negative potential such that only narrow positive peaks of a fundamental frequency input energy cause anode current to flow.

3. In apparatus for increasing the frequency of undulatory electrical currents, an electron discharge device having within an evacuated container, an anode, a cathode, and a grid, an input circuit coupled to said grid and cathode tuned to a fundamental frequency, an output circuit coupled to said anode and cathode tuned to a harmonic frequency, means for polarizing electrodes of said device so that energy of fundamental frequency appearing in said input circuit causes energy of harmonic frequency corresponding to the frequency of the tuning of the output circuit, to flow in the output circuit, and, means for rendering ineffectual the interelectrode capacitance between output and input electrodes of said electron discharge device.

4. In combination, an electron discharge device; a tunable input circuit tuned to a fundamental frequency directly connected to the input terminals of the electron discharge device; a tunable output circuit, tuned to a harmonic of the fundamental frequency, directly connected to the output terminals of the electron discharge device; means for subjecting the control electrode of the device to a negative potential such that only narrow positive peaks of fundamental frequency input energy cause anode current to flow; and, means for rendering ineffectual the capacitance between the input and output electrodes of said device.

5. In the operation of a frequency multiplier including an electron emission tube having natural capacitance and an input cir-

cuit therefor the reactance of which is capacitive for the harmonic frequency, the method of obtaining large output energy of harmonic frequency which includes the step of neutralizing or over-neutralizing the degenerative effect caused by the natural capacitance of the tube.

6. The method of augmenting the usual degree of amplification of a harmonic frequency obtained from a frequency multiplier and amplifier stage employing a three electrode tube which includes arranging the tube output circuit symmetrically for neutralization or unsymmetrically for over neutralization and thereby applying potential of harmonic frequency from the output circuit of the stage to the control electrode of the tube in phase opposition relative to the potential of harmonic frequency on the anode of the tube.

10 7. The method of obtaining large high frequency output from a neutralized power stage of a transmitter which includes the steps of feeding input energy to the input circuit of the stage, tuning the input circuit to the input frequency, tuning the output circuit to a harmonic of the input frequency, and applying from the output circuit to the input circuit an excess of neutralizing energy of the harmonic frequency.

15 8. The method of tuning a neutralized power stage of a transmitter to obtain frequency multiplication and amplification which includes the steps of tuning the input circuit to the input frequency, tuning the output circuit to one of the lower harmonics of the input frequency, and adjusting the neutralizing circuits to transfer more than the requisite amount of energy for true neutralization.

20 9. The method of tuning a capacity neutralized stage of a transmitter to obtain frequency multiplication and amplification which includes the steps of tuning the input circuit to the input frequency, tuning the output circuit to one of the lower harmonics of the input frequency, and adjusting the neutralizing condensers to values greater than that needed for true neutralization in order to obtain regenerative amplification of the harmonic frequency.

25 10. In frequency multiplying and amplifying by means of a single power stage having two electron emission tubes, the method of selectively discriminating between even and odd harmonics which includes supplying input energy to the tubes in phase opposition, and directly resonantly collecting all of the output energy from the tubes either additively or subtractively alone according as even or odd harmonics are desired.

30 11. In frequency multiplying by means of a single power stage having two electron emission tubes with series connected grids, the method of selectively discriminating between even and odd harmonics which includes supplying input energy to the tubes in phase opposition, and directly resonantly collecting all of the output energy from the tubes either additively or subtractively alone according as even or odd harmonics are desired.

35 12. In frequency multiplying and amplifying by means of a single power stage having two electron emission tubes with series connected grids, the method of selectively discriminating between even and odd harmonics and amplifying the harmonic desired which includes combining the tube outputs in parallel or in series according as even or odd harmonics are desired and feeding a portion of the harmonic output energy to the input energy in proper phase for regenerative amplification of the harmonic output energy.

40 13. In frequency multiplying and amplifying by means of a single power stage having two electron emission tubes with series connected grids, the method of selectively discriminating between even and odd harmonics and amplifying the harmonic desired which includes combining the tube outputs in parallel or in series according as even or odd harmonics are desired and feeding a portion of the harmonic output energy to the input energy in proper phase for regenerative amplification of the harmonic output energy.

45 14. In frequency multiplying and amplifying by means of a single power stage having two electron emission tubes with series connected grids, the method of selectively discriminating between even and odd harmonics and amplifying the harmonic desired which includes combining the tube outputs in parallel or in series according as even or odd harmonics are desired and feeding a portion of the harmonic output energy to the input energy in proper phase for opposing energy transferred thru natural tube capacitance.

50 15. In frequency multiplying by means of a single power stage having two electron emission tubes, the method of selecting an even harmonic and eliminating the fundamental and odd harmonics which includes supplying input energy to the tubes in phase opposition and directly resonantly collecting all of the output energy from the tubes in parallel.

55 16. In frequency multiplying and amplifying by means of a single power stage having two electron emission tubes, the method of selecting and amplifying an even harmonic and eliminating the fundamental and odd harmonics which includes supplying input energy to the tubes in phase opposition, collecting output energy from the tubes in parallel, and feeding a portion of the harmonic output energy to the input energy in proper phase.

phase for regenerative amplification of the harmonic output energy.

17. In frequency multiplying and amplifying by means of a single power stage having two electron emission tubes, the method of selecting and amplifying an even harmonic and eliminating the fundamental and odd harmonics which includes supplying input energy to the tubes in phase opposition, collecting output energy from the tubes in parallel, and feeding a portion of the harmonic output energy to the input in proper phase for opposing energy transferred thru natural tube capacitance.

18. In frequency multiplying and amplifying by means of a single power stage having two electron emission tubes, the method of selecting and amplifying an even harmonic and eliminating the fundamental and odd harmonics which includes supplying input energy to the tubes in phase opposition, collecting output energy from the tubes in parallel, and feeding a portion of the harmonic output energy to the input energy in proper phase for neutralizing energy transferred thru natural tube capacitance, but in excess magnitude in order to obtain regenerative amplification of the harmonic output energy.

19. A frequency multiplier and amplifier power stage for a transmitter comprising an electron emission tube, an input circuit tuned to an input frequency directly connected thereto, an output circuit tuned to a harmonic of the input frequency, directly connected to said tube, and means to regeneratively couple the output circuit to the input circuit to accentuate the harmonic frequency, the control electrode of said tube being subjected to a negative potential such that only narrow positive peaks of the input energy cause output current flow through said tube.

20. A frequency multiplier and amplifier stage comprising an electron emission tube having natural capacitance, an input circuit tuned to an input frequency, an output circuit tuned to a harmonic of the input frequency, and neutralizing means adjusted to feed more energy than is needed for neutralizing the energy transferred thru the natural tube capacitance.

21. A frequency multiplier and amplifier power stage comprising two electron emission tubes, an input circuit arranged to energize the tubes in phase opposition, a parallel resonant output circuit tuned to an even harmonic of the input frequency, and means to feed the output from both of the tubes directly in parallel to the resonant output circuit.

22. A frequency multiplier and amplifier power stage comprising two electron emission tubes having natural capacitance, an input circuit arranged to energize the tubes in phase opposition, an output circuit tuned to an even harmonic of the input frequency, means to connect said tubes to said output circuit in

parallel, and means to supply from the output circuit to the input circuit energy of the harmonic frequency in such phase as to oppose the effect of energy transferred thru the natural tube capacitance.

23. A frequency multiplier and amplifier power stage comprising two electron emission tubes having natural capacitance, an input circuit arranged to energize the tubes in phase opposition, an output circuit tuned to an even harmonic of the input frequency, means to connect said tubes to said output circuit in parallel, and means to supply from the output circuit to the input circuit energy of the harmonic frequency in such phase as to oppose the effect of energy transferred thru the natural tube capacitance and of excess magnitude in order to obtain regenerative amplification of the harmonic frequency.

24. A frequency multiplier and amplifier power stage comprising two electron emission tubes, an input circuit comprising an inductor and a condenser tuned to an input frequency and connected to the tubes in phase opposition, an output circuit comprising an inductor and condenser tuned to an even harmonic of the input frequency, means to connect both of said tube anodes to one side of the output circuit, means including a neutralizing condenser connecting the other side of said output circuit to the mid-potential point of the input circuit condenser, and means including a source of energy connecting the cathode to a mid-potential point of the output circuit.

25. In the operation of a power amplifier comprising cascade connected stages having tuned input and output circuits for the delivery of very high frequency power the method of stabilizing the delivered frequency by preventing spurious oscillations and rendering the tuning adjustments of the amplifier stages less critical which includes the step of frequency multiplying in the amplifier stages whereby only the last circuit is tuned to the very high frequency, and all of the circuits in the amplifier are tuned to frequencies different from one another, and, the step of biasing each amplifier such that only narrow positive peaks of input potentials cause energy flow in the output circuit of the amplifier.

26. In the operation of a frequency multiplier stage including an input circuit tuned to the lower frequency, an output circuit tuned to the higher frequency, and an electron emission tube having natural capacitance thru which degenerative energy of the higher frequency is passed, the method of making the multiplier stage more highly effective as an amplifier stage which includes neutralizing the multiplier stage in order to overcome degeneration.

27. The combination with a frequency multiplier stage having natural coupling

which permits the transfer of degenerative energy between the lower and higher frequency circuits, of means to transfer energy of like frequency and opposite phase to 5 counteract the naturally transferred degenerative energy.

28. The combination with a frequency multiplier stage including an electron emission tube having natural capacitance and an 10 input circuit which is capacitive in reactance for energy of the multiplied frequency, of means to neutralize the stage for the natural capacitance of the tube.

29. In the operation of a frequency multiplier including an electron emission tube having natural capacitance, an output circuit tuned to a harmonic frequency and an input circuit tuned to a fundamental frequency whereby it is an effective capacitance for the 20 harmonic frequency, the method of increasing the output energy of harmonic frequency which includes applying regeneration tending to overcome degeneration caused by the tube capacitance being electrically in series 25 with an effective grid-to-filament capacitance for the harmonic frequency.

30. In combination, an electron discharge device; a tunable input circuit tuned to a fundamental frequency directly connected to 30 the input terminals of the electron discharge device; a tunable output circuit, tuned to a harmonic of the fundamental frequency, directly connected to the output terminals of the electron discharge device; means for 35 subjecting the control electrode of the device to a negative potential such that only narrow positive peaks of fundamental frequency input energy cause anode current to flow; and, means for regeneratively feeding energy of 40 the harmonic frequency from the tuned output circuit to the input side of said electron discharge device.

31. In combination, a pair of electron discharge devices having their cathodes connected together; a tunable input circuit tuned to a fundamental frequency directly connected to the input terminals of said devices; a tunable output circuit tuned to a harmonic of the fundamental frequency, 45 directly connected to the output terminals of said electron discharge devices; and, means for subjecting the control electrodes of the discharge devices to negative potentials such that only narrow positive peaks of 50 fundamental frequency input energy cause anode current flow in the output circuits of said devices.

32. In combination, a pair of electron discharge devices having their cathodes connected together; a tunable input circuit, tuned to a fundamental frequency, directly connected to the input terminals of said devices; a tunable output circuit tuned to a harmonic of the fundamental frequency, 55 directly connected to the output terminals of 60

said electron discharge devices; means for subjecting the control electrodes of said devices to negative potentials such that only narrow positive peaks of fundamental frequency input energy cause current flow in the output circuits of said devices; and, means for regeneratively feeding energy of harmonic frequency from the output side of said devices to the input side thereof. 70

33. In combination, an electron discharge 75 device; a tunable input circuit tuned to a fundamental frequency coupled to the input terminals of the electron discharge device; a tunable output circuit, tuned to a harmonic of the fundamental frequency, coupled to the output terminals of the electron discharge device; means for subjecting the control electrode of the device to a negative potential such that only narrow positive peaks of fundamental frequency input energy cause anode 80 current to flow; and, means for regeneratively feeding energy of the harmonic frequency from the tuned output circuit to the input side of said electron discharge device. 85

34. In combination, an electron discharge 90 device; a tunable input circuit, tuned to a fundamental frequency, coupled to the input terminals of the electron discharge device; a tunable output circuit, tuned to a harmonic of the fundamental frequency, coupled to the 95 output terminals of the electron discharge device; and, a condenser connected in neutralizing fashion between said input and output circuits.

35. In combination, an electron discharge 100 device; a tunable input circuit, tuned to a fundamental frequency, coupled to the input terminals of the electron discharge device; a tunable output circuit, tuned to a harmonic of the fundamental frequency, coupled to the 105 output terminals of the electron discharge device; a condenser connected in neutralizing fashion between said input and output circuits; and, means for subjecting the control electrode of the device to a negative potential 110 such that only narrow positive peaks of fundamental frequency input energy cause anode current flow in the output circuit of the device.

36. In combination, a pair of electron discharge devices having their cathodes connected together; a tunable input circuit, tuned to a fundamental frequency, coupled in phase opposition to the input terminals of said devices; a tunable output circuit, tuned to a 115 harmonic of the fundamental frequency, coupled to output terminals of said electron discharge devices; condensers connected in neutralizing fashion between said input and output circuits; and, means for subjecting the control electrodes of the electron discharge devices to negative potentials such that only narrow positive peaks of fundamental frequency input energy cause energy flow in the 120 output circuit of said devices. 125

37. In combination, a pair of electron discharge devices having their cathodes connected together; a tunable input circuit tuned to a fundamental frequency directly connected in phase opposition to the input terminals of said devices; a tunable output circuit tuned to a harmonic of the fundamental frequency, directly connected to the output terminals of said electron discharge devices; means for subjecting the control electrodes of the discharge devices to negative potentials such that only narrow positive peaks of fundamental frequency input energy cause anode current flow in the output circuits of said devices, and means for preventing undesired capacitive feed back action caused by the interelectrode capacitance between input and output electrodes of said devices.

38. A frequency multiplier comprising an electron discharge device having within an hermetically sealed container an electron emitting cathode and anode and a control electrode, a circuit tuned to a fundamental frequency coupled to said control electrode and cathode, and, an output circuit for said electron discharge device tuned to a harmonic frequency of said fundamental coupled to the anode and cathode of said device, and, means, for preventing regenerative amplification of electrical energy of fundamental frequency, associated with said electron discharge device.
